UNITED STATES PATENT OFFICE.

WILBER J. SELBY AND JAMES GILBERT, OF EAGLE, IDAHO, ASSIGNEES TO ROTARY SIGN COMPANY, OF OAKLAND, CALIFORNIA, A CORPORATION OF OREGON.

ROTARY SIGN EXHIBITOR.

Application filed October 26, 1921. Serial No. 510,605.

To all whom it may concern:

- Be it known that we, WILBER J. SELBY and JAMES GILBERT, citizens of the United States, residing at Eagle, in the county of Ada and State of Idaho, have invented certain new and useful Improvements in Rotary Sign Exhibitors, of which the following is a specification, reference being had to the accompanying drawings.
- 10 This invention relates to rotary sign exhibitors and has for an important object thereof the provision of a device of this character which may be very cheaply and readily manufactured.
- 15 A further object of the invention is to provide a device of this character which, although extremely light in construction, is very strong and durable, and which may be very easily assembled.
- 20 Other objects and advantages of the invention will become apparent throughout the course of the following description.

In the accompanying drawings, wherein for the purpose of illustration is shown a preferred embodiment of our invention and wherein like reference characters designate like parts throughout:

Figure 1 is a perspective view of a rotary sign exhibitor as constructed in accordance with our invention;

Figure 2 is a perspective of the base, one of the side members being removed to show the manner of construction;

Figure 3 is a fragmentary side elevation showing the construction of the arms and manner of mounting the same;

Figure 4 is a section on the line 4—4 of Figure 3;

Figure 5 is a section on the line 5—5 of Figure 3;

Figure 6 is a fragmentary transverse sectional view taken through the exhibitor;

Figure 7 is a section taken on the line 7—7 of Figure 6;

Figure 8 is a fragmentary side elevation of one of the brace arms;

Figure 9 is a similar view of the corresponding portion of the supporting arm; and

Figure 10 is a plan view of one of the clamps therefor.

Referring now more particularly to the drawings, the numeral 10 indicates a base as a whole, comprising corner members 11 formed of angle iron. The base is rectangu-

lar in form and has the corner members thereof connected at the top and at or adjacent the bottom, by cross braces 12 to which are secured side plates 13.

The corner members 11 which are diagonally opposed have secured thereto the ends of members 14, which members are connected centrally to form an X-shaped brace forming a support for a vertical standard 16 secured to the brace 14, as at 15. This standard extends through a top member 17 secured to the upper cross members 12 of the base and projects thereabove for a considerable distance. Rotatably mounted upon the vertical standard 16 and having its lower end abutting the top member 17 of the base, is a sleeve 18. The numeral 19 indicates supporting arms corresponding in number to the number of sides with which the rotatable element R of the sign is provided. Each arm 19 is provided upon its outer end with a down-bent portion 20. These arms are preferably formed of channel iron, the down-bent portions thereof being bent so that the sides 21 thereof are arranged at an angle to one another, corresponding to the angle of the polygon forming the rotatable member R. The inner ends of each of the arms are likewise provided with down-bent portions 22, each having at the end thereof, remote from the arm, a hook 23. The down-bent portions 22 are adapted to receive the clamp 24, the hook 23 engaging beneath the lower edge thereof and preventing vertical displacement of the arm 19. A split clamp of the type shown in Figure 10 is preferably employed so that the arms may be readily inserted in the clamp and the down-bent portions 22 thereof firmly bound against the sleeve 18 in predetermined spaced relation. To support the arms 19 I provide diagonal brace arms 25 secured to the arms 19 intermediate their ends, as at 26, and extending diagonally downwardly therefrom. The diagonal brace arms are provided upon their lower ends with angular portions 27 abutting the sleeve 18 and terminating in hooked portions 28, the portions 27 being held against the sleeve 18 by a clamp 24 similar to the clamp employed for holding the ends of the arms 19 thereto.

Rectangular forms 27^a corresponding in number and arrangement to the predetermined number and size of the rotatable element R, are provided, each formed of chan-

nel iron and each adapted to have its ends secured to the adjacent sides of adjacent portions 21 of the arms 19. Within these rectangular forms are held removable and interchangeable sign members S, preferably formed of sheet metal. If desired, the upper extremity of the supports 16 may be continued above the rotatable element R and employed for holding the stationary signs, as indicated at 29 and 30.

From the foregoing it is believed to be obvious that we have constructed a rotary sign exhibitor which may be readily and cheaply constructed from sheet metal, and which may be very cheaply manufactured without sacrificing the strength and durability of the device. It will furthermore be obvious that the construction as hereinbefore set forth is capable of some change and modification without departing from the spirit of our invention, and we accordingly do not limit ourselves to the specific structure hereinbefore set forth except as hereinafter claimed.

What we claim is:

1. In a rotary sign exhibitor, a base, a substantially vertical support carried by the base, a sleeve rotatably mounted on said support, supporting arms secured to said sleeve and radiating therefrom and provided at their extremities with angular portions, brace arms corresponding in number and arrangement to said supporting arms, each having one end secured to one of said supporting arms and the other end secured to said sleeve, and signs disposed intermediate and having their ends secured to the angular

portions at the extremities of adjacent supporting arms.

2. In a rotary sign exhibitor, a rotatably mounted sleeve, arms radiating from said sleeve and having at the ends thereof angular portions, the angular portions at the inner ends of said arms abutting said sleeve, a collar surrounding said angular portions and securing the same to the said sleeve, signs arranged between and having their ends secured to the down-bent ends of the adjacent outer extremities of the arms, and braces secured to said arms intermediate the ends thereof and to said sleeve.

3. A device of the character described comprising an upstanding cylindrical support, a sleeve rotatable upon the support, arms radiating from the sleeve and having their inner ends formed with downward extensions engaging thereagainst and terminating at their lower ends in hooks, a contractile split ring encircling said downward extensions and retained by said hooks, the outer ends of said arms carrying exhibition plates, inclined braces having their upper ends connected with the intermediate portions of the arms and having their lower ends formed with downward extensions engaging against the sleeve and terminating in hooks, and a contractile split band encircling said last named extensions and retained by said hooks.

In testimony whereof we hereunto affix our signatures.

WILBER J. SELBY.
JAMES GILBERT.
